UNITED STATES PATENT OFFICE

ADOLF H. SCHAFFERT, OF ROCHESTER, NEW YORK, ASSIGNOR TO YAWMAN & ERBE MANUFACTURING CO., OF ROCHESTER, NEW YORK, A CORPORATION OF NEW YORK

FILE FOLDER

Application filed January 15, 1923. Serial No. 612,612.

This invention relates to improvements in file folders, particularly of the type adapted to be filed vertically.

The object of the invention is the provision of an improved folder of this type having means for conveniently so confining the contents of the folder as to prevent their working up and obscuring the filing legend.

The principal feature of the invention is the provision of a flap extension integral with the back of the folder, which is adapted to be turned down between the back and front portions of the folder so as to overlie the contents within the folder and prevent their working up and thus giving the file a mussy appearance and obscuring the filing legend at the top of the rear portion of the folder.

It is believed that the invention will be best understood by a description thereof taken in connection with the accompanying drawings, in which

Figure 1 is a perspective view of one form of the invention, and

Figure 2 is a similar view of a modification. Referring now to the drawings, 10 indicates the front portion or flap of the folder, and 11 the rear portion thereof. Between the parts 10 and 11 the folder is creased or scored, as indicated at 12 and 13, to provide the bottom portion of the folder. When only a very few papers are placed within the folder, the file need be bent along merely one of the creases, as 13, thus permitting the folder to occupy less space within the file. The upper edge of the rear portion 11 of the folder is rebent to form the integral flap 14. The flap 14 is creased or scored, as indicated at 15 and 16, so as to provide the outstanding portion adapted to overlie the upper edges of the papers within the folder. In the form of the device shown in Figure 1, the portion of the returned flap between the crease 15 and the upper edge of the folder is preferably pasted or otherwise secured to the back portion 11 of the folder. In this form of folder, the filing legend will preferably appear on said pasted portion of the flap at the upper left corner of the folder, as indicated on the drawing.

In using this device, the papers will be

placed within the file, substantially as in files of this character in common use. However, the flap 14 of the present file will be placed so as to overlie the contents of the folder, that is, between the outermost one of the 55 papers placed therein and the front portion 10. Thus the papers confined within the file will be prevented from working upwardly beyond the upper edge of the front portion 10 and giving the file a mussy appearance and 60 obscuring the filing legend at the upper edge of the file, hence greatly facilitating the handling of folders within the file and rendering manipulation of the folders, in searching for a particular one, easier and more expeditious.

The form of the device shown in Figure 2 is in all respects similar to that shown in Figure 1, except that the upper edge of the returned flap is not secured to the back portion 70 of the folder. Specifically, this folder consists of the front portion 17 and rear portion 18, between which the file is grooved or scored, as indicated at 19 and 20. Integral with the upper edge of the back portion 18 is the 75 returned flap 21, on the upper edge of which the filing legend may be placed in the usual manner. The method of employing the folder shown in Figure 2 is substantially the same as that described in connection with the folder shown in Figure 1.

Having thus described my invention, what I claim is new and desire to secure by Letters Patent of the United States is:

1. An open-ended folder adapted for use 85 in a filing system comprising a blank folded substantially centrally thereof to form a front and a back, said back extending above said front and being folded back on itself and projecting outwardly and then downwardly between the front and the back for overlying the contents of the folder, said outward projection of said flap being spaced a distance below the upper edge of the back to provide a space for filing information.

2. An open-ended folder adapted to be placed in a substantially vertical position in a filing system, comprising a blank folded substantially centrally thereof to form a front and a back, said back extending above said 100

front and being folded back on itself along a horizontal line, said folded portion projecting outwardly and downwardly between the front and back for overlying the contents of the folder, said folded portion being adapted to have filing information written thereon, and said folded portion being comparatively narrow in order that the papers may be readily placed in or withdrawn from the folder without removing the folder from the filing system.

3. An open-ended folder adapted to be used in a filing system comprising a blank folded substantially centrally thereof to form a front and a back, said back extending above said front and being folded back upon itself along a horizontal line above the top of the front forming a straight upper edge and an upper margin of double thickness providing a space for filing information, said folded portion projecting outwardly and then downwardly between the front end and the back for overlying the contents of the folder.

4. An open-ended folder adapted to be used in a filing system comprising a blank folded substantially centrally thereof to form a front and a back, said back extending above said front and being folded back upon itself along a horizontal line above the top of the front forming a reinforced upper margin on the back providing a space for filing information, said folded portion projecting outwardly forming a spacer and extending downwardly between the front and the back a relatively short distance for overlying the contents of the folder.

5. An open-ended folder adapted to be used in a filing system comprising a blank folded substantially centrally thereof to form a front and a back, said back being folded back upon itself forming a straight reinforced upper margin extending above the top of the front adapted to have filing information written thereon, said folded portion projecting forwardly, horizontally at the height of the upper edge of the front to form a spacer, and then extending downwardly a short distance between the front and the back for overlying the contents of the folder.

50. 6. An open-ended folder adapted to be used in a filing system comprising a blank folded substantially centrally thereof to form a front, a back and a horizontal bottom, spacing the front from the back at their lower edges, the upper edge of the back folded back upon itself forming a reinforced upper margin and a flap integral therewith, said flap projecting forwardly, horizontally a spaced distance below the upper edge of the back to substantially the upper edge of the front, then downwardly between the front and the back for overlying the contents of the folder.

In witness whereof, I hereunto subscribe my name this 9 day of Jan., 1923.

ADOLF H. SCHAFFERT.
